SELECTIVE SINGLE CONTROL MECHANISM

Fred H. Barger, Dayton, Ohio

Application May 23, 1945, Serial No. 595,460

2 Claims. (Cl. 192—48)

1

This invention relates to control mechanism and especially to switchboard, dashboard or panel controls of the type having a control knob, handle wheel or lever which is capable of selectively operating at least two different power or motion transmission mechanisms. The invention has for its general object to provide a simple and efficient mechanism in which the selective adjustment is performed by a small axial displacement of the control knob, wheel, handle or lever.

The invention essentially consists in a rocking or rotating central member associated with the control knob, handle or lever, capable of axial movement and provided with two coupling or clutch mechanisms, positively engaging and releasing, respectively, other axially fixed rocking or rotating members connected or coupled with the transmission of power or motion to be selected when moved axially in either direction. The central knob or handle operated member, according to the preferred embodiment of the invention may be held permanently in a position in which it is in operative or coupling engagement with one of the cooperating axially fixed members by means of a spring; in such a case when the knob, handle or lever is operated without axial pressure, one of the transmissions of motion or power is selected automatically while application of pressure during rotational or rocking movement causes selection of the other transmission.

The invention is more specifically described in the following detailed specification and illustrated in the accompanying drawing showing one modification thereof. It is, however, to be understood that the fact that only one preferred embodiment of the invention is described is not to be understood in a limitative sense. This modification is clearly described in terms suggesting further modifications to the expert skilled in this art and such further modifications, as far as coming within the ambit of the annexed claims, are, therefore, not to be considered as departures from the invention.

In the drawing:

Figure 1 is an elevational partly sectional view of an arrangement embodying the invention.

Figure 2 is an elevational front view of the panel and knob.

Figures 3, 4 and 5 are views of details connected with the coupling.

It has been assumed that the selective dual control, as illustrated in the drawing, is applied to a radio receiver or transmitter, to the dashboard of a car or airplane or to any other control board of some kind, and that, therefore, the

2

mechanism is arranged behind a board 6 provided with a hole 7 through which the control knob 8 only projects. This knob, as shown in Figure 2, is, therefore, the sole member which is seen and accessible from the outside or front of the board.

Associated with the knob 8 is the central coupling member 9 which is loosely mounted on a shaft 10, journaled in a support 11 at 12 and 13. The shaft may be provided with collars 14 for holding it against axial displacement.

Said shaft 10 may carry the pulley or disk 15 for one of the two transmissions of power or motion to be serviced by the dual control mechanism.

For instance, if associated with a radio receiver the pulley 15 may drive the usual cord, belt or spiral spring cord operating the volume control, the back feed control, the potentiometer or condenser to be operated selectively.

The pulley 15 in the example shown is fixedly connected with the shaft by means of its hub portion 16 through which a screw 17 is passing.

The second transmission to be coupled selectively with the member 9 and knob 8 is loosely mounted on shaft 10 and is represented in the example shown by the spur wheel 18; it is, however, to be understood that this showing is arbitrary and that any other transmitting means such as a pulley, disk or the like may be mounted in its place, as specific conditions may require.

The selective coupling of the two members 15 and 18 with the knob 8 is obtained by means of the member 9, which is mounted loosely on shaft 10 and is capable of axial displacement. This member 9 (Figures 1 and 4) is provided with two recesses 19, 20 which constitute female members provided with teeth as shown in Figure 4 or simply of polygonal or square shape. The female member 9 cooperates with a male member 21 of corresponding shape (Figure 5) formed by a toothed wheel or polygonal or square disk, which is fixed on shaft 10 by means of screw 22.

The member 9 is urged toward the member 21 by a spring 23, which finds its support on the toothed wheel 18. The female part 20 of member 9 cooperates with a male member 24 projecting from the hub portion 25 of toothed wheel 18. The male member 24 is held out of engagement with female member 20 by spring 23.

It will be clear from the above description that if knob 8 is turned without applying any axial pressure to it, the knob will turn member 9 and by means of female portion 19 and male portion 21 fixed on shaft 10, the latter will be turned

with the knob. The movement of the shaft will result in rotation of pulley 15 and in the actuation of the instrument or element operated thereby. It will also be clear that male portion 24 projecting from hub 25 of wheel 18 is not affected by this rotation of knob 8 but remains at rest.

If knob 8 is rotated with axial pressure applied to it, the member 9 will be moved axially on shaft 10, the spring 23 will be compressed, the female portion 19 will be disengaged from male portion 21 and the female portion 20 will engage male portion of disk 24. Therefore, the shaft 10 will remain at rest, while wheel 18 is turned.

It is quite obvious that the constructive details shown in the drawings may be changed and have to be changed in accordance with the special constructive purposes to be accomplished, but that this does not involve any change of a basic nature.

I claim:

1. A selective control mechanism for operating a plurality of motion transmitting members mounted behind a panel selectively by means of a single control member arranged in front of the panel, comprising a shaft mounted behind the panel provided with a portion projecting through the panel, motion transmitting members on said shaft, one of said members being mounted fixedly and one of said members being mounted loosely on said shaft, a coupling member fixed on the shaft portion projecting through said panel, an axially shiftable control member and a hand operated knob associated with the same loosely mounted on the portion of the shaft projecting through the panel between the aforementioned coupling member and the loosely mounted motion transmission member, means for effecting a rotational coupling formed on each side of said axially movable member and coupling means engageable therewith on said fixed coupling member and on said loosely mounted transmission member.

2. A selective control mechanism for operating a plurality of motion transmitting members mounted behind a panel selectively by means of a single control member arranged in front of the panel, comprising a shaft mounted behind the panel, having a portion projecting through said

panel, a coupling member fixed on the shaft portion projecting through the said panel, a motion transmitting member fixed on said shaft and another motion transmitting member loosely mounted on said shaft, both arranged behind the panel, the latter member being arranged at a distance from said coupling member, a hand operated control knob and an axially movable member connected with it, the former being arranged in front of the panel and both being slidably arranged on the projecting portion of the shaft, said axially movable member being moreover located between the two aforesaid motion transmitting members, female coupling members arranged in recesses, formed on both sides of said axially movable member, male coupling members adapted to enter said female coupling members alternatively upon movement of the axially movable member, arranged on said coupling member and on said loosely mounted motion transmission member respectively, and a compression spring between said loosely mounted motion transmission member and said axially movable member holding the female coupling part of said axially movable member out of engagement with the male member of the loosely mounted motion transmission member and the female member on the slideable and axially movable member in engagement with the male member associated with the fixedly mounted coupling member.
